UNITED STATES PATENT OFFICE.

WILLIAM H. WEASER, OF PITTSFIELD, MASSACHUSETTS.

ATTACHMENT FOR PHONOGRAPIHS.

1,426,693.

Specification of Letters Patent. Patented Aug. 22, 1922.

Application filed September 13, 1920. Serial No. 409,751.

To all whom it may concern:

Be it known that I, WILLIAM H. WEASER, a citizen of the United States, residing at Pittsfield, in the county of Berkshire and 5 Commonwealth of Massachusetts, have invented an Improvement in Attachments for Phonographs, of which the following description, in connection with the accompanying drawings, is a specification, like characters on the drawings representing like parts.

This invention relates to phonographs and other sound reproducing instruments wherein mechanical spring motors are employed as the motive agency for operating the driving mechanism.

The object of the invention is to provide simple and efficient mechanism for winding up the motor spring by foot power.

With the foregoing and other objects in view the invention consists in the construction, combination, arrangement and operation of parts as hereinafter described and pointed out in the claims, a specific useful form of embodiment thereof being herein- 25 after described and illustrated in the accompanying drawings, wherein

Figure 1 is a longitudinal vertical section of a phonograph cabinet on the line A—A of Fig. 2 looking in the direction of the 30 arrows, and showing a side view of my device operatively mounted therein;

Fig. 2, a longitudinal vertical section of the same, showing a front edge view of my device, a portion of the cabinet being broken 35 away;

Fig. 3, an interior detail plan view of the gear members cooperating with the winding shaft;

Fig. 4, a detail rear edge view of the 40 same; and

Figs. 5 and 6, detail top and edge views, respectively, of the foot pedal which is attached to the power lever.

The mechanism of my device is controlled 45 through the medium of a pedal 1, which is conveniently arranged near the bottom of the phonograph cabinet 2 within reach of the operator's foot. As shown, this pedal is pivotally attached to the lower end of a 50 reciprocating rod 3 arranged in upright position within the cabinet and extending through an opening in the bottom thereof. the jointed relation of the pedal and rod being designed to allow relative movement of 55 the pedal in a horizontal plane, so that when at rest the pedal may be swung underneath

the cabinet and out of exposed position. Suitable locking means may be provided to retain the pedal in either the exposed or hidden position, and for this purpose I have 60 shown a yielding spring pawl 4 attached to an angle support 5 provided on the lower extremity of the rod 3 and positioned to register with suitable notches 6, provided on the rear rim of the pedal and arranged to correspond with its limits of axial movement.

The rod 3 is guided in its movements by a yoke bracket 7 enclosing the rod and secured to the side wall of the cabinet near the bottom, the upper extremity of the rod 70 being pivotally attached to the forward end of a transversely arranged lever 8 by suitable terminal members 9, 10, provided thereon and having corresponding tongue and groove formations. Reverse action or upward movement of the rod 3 is controlled by means of an expansion spring 11 suspended at one end above the rod on the wall of the cabinet and secured at its opposite end to the terminal member 10 of the 80 lever 8.

The force supplied by the operator's foot is transmitted by indirection through a series of cooperative mechanical members which are designed, arranged and adapted 85 within the prescribed limits of space to transform reciprocating into rotary motion for revolving a shaft 12, which is normally provided within the phonograph cabinet for winding up the motor spring (not shown) 90 to which it is attached. The lever 8, to one end of which the rod 3 is attached, oscillates in the plane of the rod 3 upon a pivot 13 secured to the cabinet wall, the portion of its length between the rod 3 and the pivot 95 13 being preferably greater than the remaining portion. Said lever 8 is provided at its opposite end with a head 14, forming a lateral extension which is pivotally connected through a series of jointed transmission rods 15, 16, extending upward to the lower end of an arm 17 provided on a web-gear sector 18 mounted to swing between parallel casing plates 19, 19, secured to the wall of the cabinet near the shaft 12. 100 Said rods 15, 16, are disposed normally at a slight angle to each other and pivoted together by means of suitable interconnecting heads 20, 21, the opposite extremities of the rods being also provided with heads 22, 23, 110 forming pivotal connections with their corresponding points of support. Said rods 15,

16, are preferably each provided centrally with an angle in their length to form an offset portion to receive a head 24 pivoted to the heads 20, 21, and provided on the 5 lower end of an upright swinging arm 25 which carries at its upper end a head 26 pivoted to a bracket 27 secured to the wall of the cabinet 2. The arm 25 provides a movable point of support for the rods 15, 16, 10 automatically adjusting itself to any position within the limits of the arc of its swing required by the shifting relation of the rods, at the same time operating as a retaining member and guide for directing the 15 movements of the rods.

For convenience in attaching my device to the cabinet wall and to properly maintain the bracket 27 and pivot of the lever 8 in fixed relation I provide a base in the form 20 of a rigid metal strip 28 upon which these parts are permanently mounted, the strip being preferably extended upward and attached to the inner casing plate 19, thereby permitting the parts mounted thereon and 25 attached thereto to be removed and replaced as a unitary assembly.

The gear sector 18, which is pivoted between the casing plates 19, is arranged to mesh with a pinion 29 mounted to rotate 30 freely upon a shaft 30 journaled in the plates 19, the hub 31 of the pinion 29 being extended laterally to support at its opposite end a ratchet 32 which is arranged to engage 35 with a spring-pressed pawl 33 carried on one side of a gear wheel 34 keyed on the shaft 30 in adjacent relation to the ratchet 32. Said ratchet and pawl are so arranged that the downward swing of the sector 18, operating through the medium of the pinion 40 29, causes the gear wheel 34 to revolve with the pinion 29, while the reverse movement of the sector serves to revolve the ratchet only and does not affect the gear wheel. The gear wheel 34 is arranged permanently in 45 mesh with a separate gear wheel 35 carried on a shaft 36, which is journaled in the casing plates 19, 19, and in alignment with the winding shaft 12. Said shafts 12, 36, are detachably connected preferably by means of 50 a slot 37 provided in one end of the shaft 36 which is extended beyond the supporting plate 19 and adapted to receive an extension of corresponding proportions provided on the outer end of the winding shaft. The 55 relative proportions of the pinion 29, the gear wheels 34, 35, and the ratchet 32, are designed to impart to the winding shaft an accelerated speed requiring a comparatively brief interval of time and slight expenditure 60 of energy on the part of the operator to fully wind up the motor spring.

The reverse or upward movement of the sector 18 is preferably limited by means of a positive stop herein shown in the form of 65 a rigid stud 38 projecting into the path of

the sector arm 17 from the inner face of one of the casing plates 19.

The structural character and arrangement of the mechanism constituting the connection between the rod 3 and the sector 18 are 70 designed to secure within the limits of the space provided the required leverage and force to wind up the motor spring. The jointed connection and indirection of movement of these parts provide a system of compensation adapted to insure a uniform throw of the sector 18, and to break up and prevent violent or sudden strains and shocks, which otherwise might be imparted to the winding mechanism. 80

While the primary function of the lever 8 is to increase the force imparted thereto by the rod 3, this member also serves in some measure by its angular relation to and jointed connection with the reciprocating rod to 85 resist sudden or jerky movements on the part of the latter which would have an injurious effect upon the gears of the winding mechanism and upon the motor apparatus. This latter function is more effectively performed, however, by the rods 15, 16, and arm 25, which cooperate to retard speed while transmitting the motive force. The arm 25 is particularly adapted to receive the shocks of excessive motion and to 90 deflect straight line movements in a lateral direction, by which it serves both to retard speed and to prevent the elevation of the transmission member to a point beyond the limits of the sector arm 17. The rods 15, 16, 100 together constitute a unitary transmission member possessing at a central point a joint or elbow which the arm 25 is adapted to properly flex in order to obtain the necessary shortening of the transmission member 105 in lengthwise movement to insure an even and uniform swing of the sector 18.

Among the advantages derived by the use of my device are the comparative ease of operation in preference to the previous practice of winding up the motor spring by hand, and also economy of time whereby the operator is now enabled during the winding operation to employ his hands to arrange the music record and stylus. 110 115

I claim:

1. In a device of the class described, in combination, a winding shaft, speed-increasing gearing for rotating said shaft, means connected with said gearing for transforming reciprocating motion into rotary motion, a pedal, and means connecting the pedal with said motion-transforming means, including means for increasing the motive force applied to the pedal. 120 125

2. In a device of the class described, in combination, a winding shaft, speed-increasing gearing for rotating the winding shaft, a member for transforming reciprocating motion into rotary motion and arranged to 130

actuate said speed-increasing gearing, a pedal, and a series of pivotally connected members connecting the pedal with said motion-transforming member, including a lever for augmenting motive force applied to the pedal.

3. In a winding attachment for phonographs, a winding shaft, a gear fixed on the shaft, a separate shaft, a speed-increasing gear fixed on said separate shaft and arranged to mesh with the first-mentioned gear, a pinion loosely mounted on said separate shaft, a ratchet mounted to move with the pinion, a pawl carried on said speed-increasing gear and arranged to contact with the ratchet to revolve said gear in one direction only, an oscillating gear member arranged in mesh with said pinion, a pedal, and means for transmitting motion from said pedal to said gears for rotating the winding shaft.

4. In a device of the class described, a frame for attachment to a phonograph casing, a shaft journaled in the frame and extending through one side thereof into position for attachment to a winding shaft carried by the casing, a gear mounted on said shaft, a separate shaft journaled in the frame, and a speed-increasing gear mounted thereon and meshing with said first-mentioned gear, a pinion loosely mounted on said last-mentioned shaft, a ratchet mounted to move with the pinion, a pawl carried by said last-mentioned gear and arranged to coact with said ratchet to revolve said gearing in one direction only, a third shaft journaled in said frame and a gear sector mounted thereon and arranged to mesh with said pinion, said gear sector having a radial extension, means for limiting the movements of the sector, a foot pedal carried by the casing, and a series of jointedly connected arms movably connected to the pedal and to said sector extension and including a lever for transmitting motion to the gearing and the winding shaft.

5. In a device of the class described, a winding shaft, speed-increasing gearing arranged to rotate the winding shaft, and means for transmitting motion to said gearing by foot power including a pedal, a re-

ciprocating rod secured to said pedal, spring means for retracting said rod when actuated by the pedal, a force-amplifying lever mounted to swing in the casing, and pivotally secured at one end to the inner end of said rod, and a series of jointedly connected arms pivotally connected to the opposite end of said lever, and arranged to transmit motion imparted by the lever in an angular direction to said gearing.

6. In a device of the class described, the combination with a shaft, of means for revolving the shaft by foot power, and including a reciprocating member, a rotary member movably connected to said shaft, an oscillatory member movably connected to said rotary member, and transmission means for imparting motion from said reciprocating member to said oscillatory member whereby said oscillatory member is moved in an even uniform manner, and including a longitudinal member having a joint in its length and means for flexing said longitudinal member.

7. In a device of the class described, the combination with a shaft, of means for revolving the shaft by foot power, and including a rod arranged for reciprocating movement, means for reversing the action of the rod when moved in one direction by a force independent thereof, a lever pivoted to a support and movably secured to said rod, a series of gear members arranged in mesh and adapted when moved to rotate said shaft in one direction, means, including a ratchet and a registering pawl carried by said gear members, for preventing said shaft being reversely rotated, an oscillatory member having an arcuate toothed portion arranged in mesh with one of said gear members, a power transmission member movably connecting said lever with said oscillatory member and including arms arranged end to end, and forming a joint, and means for flexing said power transmission member at said joint to provide a uniform movement of the oscillatory member.

In testimony whereof, I have signed my name to this specification.

WILLIAM H. WEASER.
